[57] ABSTRACT

A machine for washing and/or filling containers comprises at least one treatment station, the station having a fixed washing or filling head at the bottom of the station and a support cradle for an inverted container, the cradle having a lower support surface to support an inverted container above the head and an upper bearing surface, the two surfaces being spaced apart by a sufficient distance for a container to be placed in the cradle, the cradle being moveable downwardly to lower the container onto the head and to clamp the container between the head and the upper bearing surface ready for treatment by the head.

WASHING AND FILLING MACHINES

FIELD OF THE INVENTION

The invention relates to washing and/or filling machines, for example machines for washing and/or filling beer kegs.

DESCRIPTION OF THE PRIOR ART

Washing and/or filling machines are known having one or more treatment stations, each station having means to wash or fill a container, the means including a vertically moveable washing or filling head at the bottom of the station. In use the head is raised to engage an opening of an inverted container, and an upper support is lowered to press the container firmly onto the head before the inverted container is washed or filled.

SUMMARY OF THE INVENTION

It is an object of the invention to provide a washing and/or filling machines using fewer moveable parts, and in particular having a fixed treatment head.

In accordance with this object the invention provides a machine for washing and/or filling containers (e.g., beer kegs) comprising at least one treatment station, the station having a fixed washing or filling head at the bottom of the station and a support cradle for an inverted container, the cradle having a lower support surface to support an inverted container above the head and an upper bearing surface, the two surfaces being spaced apart by a sufficient distance for a container to be placed in the cradle, the cradle being moveable downwardly to lower the container onto the head and to clamp the container between the head and the upper bearing surface ready for treatment by the head.

In use a container is placed in the cradle and the cradle is then lowered to clamp the container onto the head. After the washing or filling operation has been completed, the cradle is raised and the container removed.

The upper bearing surface may be mounted on the cradle for lost-motion in the vertical direction. This is advantageous when the machine is to be used for treating containers of differing heights.

The invention includes a machine for washing and/or filling containers (e.g., beer kegs) comprising at least one treatment station, the station having a fixed washing or filling head at the bottom of the station, and a support cradle for an inverted container comprising an upper bearing surface, means to move the bearing surface vertically and a lower support surface connected to the upper bearing surface for vertical lost-motion with respect thereto, the cradle being moveable by said means between a first position in which the two surfaces are spaced apart by a sufficient distance for an inverted container to be placed on the lower support surface, the lower support surface being suspended above the head at the lower limit of its lost-motion, and a second position in which the container has been lowered onto the head and is clamped against the head by the upper bearing surface.

The moving means may comprise a piston and cylinder combination.

Where the machine comprises a combined washing and filling machine having a washing station and a filling station, a cradle as described above may be pro-

vided at each station when washing and filling are both carried out on inverted containers. Where filling is carried out on upright containers, the machine including means to turn a container over between washing and filling, a cradle may be provided at the washing station only.

BRIEF DESCRIPTION OF THE DRAWINGS

FIG. 1 is a longitudinal section through the washing station of a machine according to the invention; and

FIG. 2 is a view of the station in the direction of entry of containers.

DESCRIPTION OF THE EXAMPLE

15 The machine has a fixed frame, an upper part of which is shown at 10 and a lower base part, on which a washing head 11 is rigidly mounted, is indicated by reference numeral 10a. Pipes 12, 13, are connected to the head to carry washing fluid to and from the head.

20 Also mounted on the frame is a cradle 14. The cradle comprises a lower support surface 15 and 15a, an upper bearing surface 16 and 16a, and two side members 17.

25 The lower support surface comprises essentially a pair of spaced beams 15a which are capable of supporting an inverted beer keg with the neck of the keg projecting downwardly between the beams. The beams 15a are secured in a rectangular frame 15 secured rigidly to side members 17. Also, the upper support surface includes essentially a pair of spaced beams 16a secured to a beam 16.

30 Each side member 17 has at its upper end a slot 18 therein. Upper support surface 16 comprises a transverse beam mounted for lost-motion in slots 18 by means of spigots 23 at the ends of the transverse beam.

35 The beam 16 is connected to piston rod 19 of a pneumatic piston and cylinder combination 20. The cylinder 21 is rigidly mounted on frame 10.

40 Spaced members 22 are provided to guide the cradle for vertical motion under the control of piston and cylinder combination 20. Members 22 are each connected to the fixed frame of the machine.

45 In use an inverted keg is positioned in the cradle with its neck over the fixed washing head 11. Piston and cylinder combination 20 is then activated to lower beam 16 and the remainder of the cradle and the container move downwardly with beam 16 under gravity.

50 The keg is brought to rest by the engagement of head 11 in the neck of the keg. Support 15 and uprights 17 are brought to rest shortly after by portions (not shown) of the machine frame arranged just below the head 11. The spacing of support 15 below head 11 is arranged so that it will still support the keg sufficiently to prevent it toppling off head 15.

55 After support 15, uprights 17 and the keg have been brought to rest beam 16 continues to move, travelling down slots 18 until it abuts the upward facing base of the keg and clamps the keg firmly onto the washing head.

60 After washing has been completed, the cradle is returned to the position shown by piston and cylinder combination 20 and the keg is removed.

65 The apparatus described in this example enables a keg to be supported above a washing head before and after washing, and to be positively applied to the head

for washing, utilising a single piston and cylinder combination.

The invention is not restricted to the features of the foregoing example. For instance, where all the containers to be washed are of the same height, beam 16 may be fixed relative to side members 17, and arranged at such a height that during lowering of the cradle beam 16 engages the base of an inverted container just as the keg engages head 15.

I claim:

1. A machine for washing and/or filling containers, comprising at least one treatment station, the station having a fixed washing or filling head at the bottom of the station and a support cradle for an inverted container, the cradle having a lower support surface to support an inverted container above the head and an upper bearing surface connected to the lower support surface as an integral part of the cradle, the upper bearing surface being mounted on the cradle for lost-motion in the vertical direction, the two surfaces being spaced apart by a sufficient distance for a container to be placed in the cradle, and the cradle being movable downwardly to lower the container onto the head and to clamp the container between the head and the upper bearing surface ready for treatment by the head.

2. A machine as claimed in claim 1 in which the two surfaces each comprise at least one beam.

3. A machine as claimed in claim 1 in which spigots on the upper bearing surface engage in slots on the cradle.

4. A machine as claimed in claim 1 including means to move the cradle.

5. A machine as claimed in claim 4 in which the moving means comprise a piston and cylinder combination.

6. A machine as claimed in claim 4 in which spigots on the upper bearing surface engage in slots on the cradle.

7. A machine for washing and/or filling containers comprising at least one treatment station, the station having a fixed washing or filling head at the bottom of the station, and a support cradle for an inverted container comprising an upper bearing surface, means to move the bearing surface vertically and a lower support surface connected to the upper bearing surface for vertical lost-motion with respect thereto, the cradle being moveable by said means between a first position in which the two surfaces are spaced apart by a sufficient distance for an inverted container to be placed on the lower support surface, the lower support surface being suspended above the head at the lower limit of its lost-motion, and a second position in which the container has been lowered onto the head and is clamped against the head by the upper bearing surface.

25 8. A machine as claimed in claim 7 in which the moving means comprise a piston and cylinder combination.

9. A machine as claimed in claim 7 in which the two surfaces each comprise at least one beam.
